10 Claims. (Cl. 209—323)

This invention relates to mechanically operated screens. It is applicable, e. g., to rotating or to shaking screens, which last may use reciprocating and gyratory motion.

According to the present invention there is provided a method of maintaining a mechanical screen in more efficient condition while screening material, which comprises providing at least one hollow body of such configuration that it is resilient and capable of bouncing, and arranging that the said body or bodies are caused to bounce against a screening surface or surfaces of the screen through the instrumentality of the motion of the screen so that passage of the material through the apertures of the screen is facilitated. Preferably the hollow bodies are caused to bounce against the underside of the screening medium. In its preferred form the hollow body takes the form of a detached unrestrained coil spring.

Suitable springs are coil springs shaped in major part so that the imaginary surface in which the outermost diameters of the coils of the spring lie is substantially a surface of revolution having double curvature and which when viewed from the exterior is convex. The surface is preferably spherical, but may also take other forms, such as spheroidal or ellipsoidal or even paraboloidal. In general the more nearly the surface approaches spherical the better the results.

The invention is of particular value in its application to mechanically operated screens having one, or having two or more decks. In screens of this type there are commonly provided superimposed units, each fitted with a cloth having a mesh of lesser aperture than the cloth above it, and the whole is shaken by a suitable mechanism. The movement may be gyratory or oscillating and is commonly effected by means of an eccentric drive. For example, the eccentricity employed may be $1\frac{3}{4}$ " giving a total longitudinal throw of $3\frac{1}{2}$ " and there may be 200 cycles per minute. The invention is of special value where the amplitude of the movement is appreciable, for example $\frac{1}{2}$ " and more.

In order to keep the meshes of such screens free, especially when the material being screened is fine, it has been the practice to make each deck in the form of a unit comprising a screening sheet of desired mesh and an auxiliary sheet of coarser mesh situated beneath the first and spaced therefrom; to provide between each screening sheet and its auxiliary sheet a frame divided into a number of compartments, which rests on the auxiliary sheet; and to place in each compartment a number of solid rubber balls. While the compartments may be of any suitable shape, for example diamond, they are preferably oblong or square and formed by longitudinal and transverse members. For compartments which are 15" square there may be 3 or 4 balls in each compartment, for example.

Preferably each frame extends close up to each of the cloths between which it lies, and the transverse members of the frame are shaped so that they each present in-

2

teriorly to the compartment a plane face inclined at an obtuse angle to the lower, i. e., the auxiliary cloth. This angle may be for example between 120° and 105° . Under the effect of the motion of the screen the balls are projected, come into contact with the inclined faces of the transverse members and rebound therefrom against the underside of the cloths, thereby shaking the latter and thus facilitating passage of the material through the cloths and tending to keep them clean.

However, it has been found in practice with abrasive and/or hot materials that the balls wear and lose their efficiency. This results in increased costs due to replacement of the balls, and dismantling of the screen. Although we have tried solid and hollow balls made from a large number of materials, we have been unable to find any that gave satisfactory performance under these conditions.

It has also been previous practice to make the aforesaid framework of wood on account of the lightness it confers, but screens with such frameworks suffer from the further disadvantage that the wood soon fails when they are used for the screening of hot and abrasive materials. The screening of hot and abrasive materials is an operation of wide commercial use, since it is common practice, on account of the economies achieved, to screen dried materials immediately after drying, and the material may be at a temperature of, for example, up to 115° C. or more. This applies, for example, to the drying of fertilizers or ores.

According to a preferred feature of the invention, therefore, there is provided a method of maintaining a one, two, or multi-deck vibrating screen in more efficient condition whilst employed in screening material which comprises providing each deck with a number of compartments on the underside by means of suitably disposed metal structural members and providing in at least some of the compartments at least one detached metal coil spring shaped in major part so that the imaginary surface in which the outermost diameters of the coils of the spring lie is substantially a surface of revolution having double curvature and which, when viewed from the exterior is convex.

40 causing the said coil springs to bounce against the underside of the screening cloths through the instrumentality of the motion of the screen, thereby facilitating passage of the material through the apertures of the screening cloths. The transverse sectional members, and preferably also the longitudinal ones, are shaped so that they present inclined faces interiorly to each compartment, as already described, from which the moving coil springs can rebound. It will be obvious that with such a screen having, for example, a total longitudinal throw of $3\frac{1}{2}$ " and moving with a frequency of 200 cycles per minute the springs will impinge against the screens very many times per minute. We have in fact found that their action is very effective in keeping the cloths clean and in increasing screening rates. It is preferred to have only one spring in each compartment of the framework. Better cleaning of the screening surfaces may be achieved

50 by the use of several springs in each compartment, so long as the springs remain detached from one another. However, on account of the tendency for the springs to become attached to one another, it is preferred to use one spring in each compartment. The springs also reduce build-up of fine material on the sides of the compartments.

A suitable apparatus in which the method of the present invention may be conducted is illustrated in Figures 3 and 4 in the accompanying drawing, in which Figure 3 is a longitudinal cross section, illustrating the invention in a preferred form in its application to a three-deck gyratory screen, and Figure 4 is a perspective view show-

ing one of the compartments in a deck of such a screen from which the screening sheet has been removed.

Referring to Figures 3 and 4, 1 represents the screening box; 2 a drive head, driven through shaft 3 by a motor, for applying the gyratory motion to the screen; 4 the inlet sleeve; 5, 6 and 7 the three decks; and 8, 9, 10 and 10a the outlet sleeves for the screened material. Each deck comprises a screening sheet 11, carried in a frame 12; an auxiliary sheet 13 situated at an appropriate distance, e. g., about 1½" to 2½" below the screening sheet 11 and carried in the same frame 12; a compartmented metal frame resting on the auxiliary sheet 13 and consisting of longitudinal and cross members, 14 and 15, respectively; and in each of its compartments a detached spherical spring 16. The cross members 15 are of trapezium-like cross section, thus presenting interiorly to the compartment a plane face 17 inclined at an obtuse angle to the auxiliary sheet 13. The drive head is of known type and comprises, for example, a cam driven through bevel gearing, which imparts a gyratory motion to the driven end of the screen by means of a pivot 2a engaging a socket 2b on the screen box. The non-driven end of the screen moves in longitudinal slides.

The arrows show the direction of movement of the material being screened.

As a further feature of the invention, especially where materials are being screened hot, the frame encasing the screens and the members forming the compartments are made of metal, especially stainless steel. In order to keep down weight and thereby save power, the sections forming the compartments should be as light as possible, e. g., of 20 British Standard wire gauge. With such frames it was, however, found that solid balls made of temperature and abrasion resistant material, which were otherwise satisfactory, failed because they dented the light metal frames. Denting results in the balls not bouncing properly on to the cloths. The coil springs herein described did not do this, and have maintained their efficiency over long periods without apparent deterioration.

When the material being screened is abrasive it is preferable that the screening media, springs, casing and frames be of metal, for example, of stainless steel.

When the material being screened is hot it is preferable that the screening media, springs, casing and frames be of metal, e. g., stainless steel.

When the material being screened is a foodstuff it is preferable that the screening media, springs, casing and frames be of stainless steel.

When the material being screened is corrosive it is preferable that the screening media, springs, casing and frames be of stainless steel.

When a heavy material such as ore is being screened it is desirable that the screen, springs and frame members should be robust. This in general means heavier equipment and more powerful driving means.

The coils of the spring may be substantially contiguous, but preferably they are spaced. The configuration, dimensions and spacing of the coils are chosen so that the material being screened does not build up or cake and so produce a more or less solid unit, which would deprive the springs of their advantages of resiliency and lightness. One way of achieving this is to provide adequate free space between the coils to allow the material to pass through and not pack the coils. The characteristics of the coils are varied depending on the mesh size of the screens and on the properties, especially grading, of the product. For general purposes the springs may be formed, for example, of mild steel, high carbon steel, alloy steels, Monel metal, or bronze, but non-corrosive metals are generally preferred.

Suitable spherical springs are made of steel rod or wire, e. g., of from 0.048 to ¾" diameter. Typical suitable spherical coil springs have the characteristics given

in the following table. They weigh about one third of a similar rubber ball.

	Outside diameter of coil, ins.	Diameter of wire, British Standard wire gauge	Pitch of coils, mms.	Weight of coil, gms.
10	1½	12	5	26
	1¾	16	3	27
	1¾	18	2.25	15

The spherical springs are made by feeding cold rod or wire through a die to a substantially spherical mandril, provided with spiral grooves, under tension and, if ordinary steel is used, thereafter hardening the steel by passing the coil into a cyanide bath at about 150° C. High carbon steels are preferred to mild steels, and austenitic steels, especially stainless steels, are more preferred on account of their good corrosion resistance. It is preferred to have the spherical springs as near true spheres as possible so that they do not assume a dead position, i. e., with the axis of the spring parallel or perpendicular to the screen, but bounce as much as possible. It is an advantage to bend each end of the coil into a small arch at the extremities of the sphere and to tuck the loose ends inside the spring.

A spring found to be very suitable for screening hot fertilizer at 115° C. between the meshes of a gyratory 3 deck screen having apertures of 10, 5 and 0.5 mm. respectively with 12 mm. aperture auxiliary sheets which had a throw of 1¾" at a frequency of 200 cycles, had the following characteristics.

The axial length of the spring was 1½" and the equatorial diameter 1¾", and it was formed of ½" stainless steel rod with a pitch of 15¾" at the centre, reducing towards the poles.

The invention is illustrated by the following example.

Example

Firstly operation according to the prior art will be described. The screen employed had three decks, each with a screening surface of 10' by 5'. These decks were fitted respectively with screening cloths having 4.02 mm., 2.0 mm. and 0.75 mm. apertures, and with auxiliary sheets having 6 mm. apertures. The frames were of stainless steel of 20 Standard wire gauge sheet each weighing approximately 100 lb. Each frame was divided into 40 compartments, in which the transverse faces of the frames were inclined at about 115° to the lower cloth. The screen was used to screen mixed artificial fertilizer which had been dried and had to be screened at a temperature of 115° C. Originally 3 solid resilient rubber balls were installed in each compartment, making 360 balls in all, and the screen was put into service for 6 weeks. During this period the balls became reduced from 2" to ½" diameter and consequently became ineffective in cleaning the screens. This necessitated replacing 60 balls each week and the stainless steel cloth fastenings had therefore to be lifted regularly, which necessitated the complete dismantling of the screen at least once per week. This meant considerable loss of running time and involved considerable expenditure.

Similar results were obtained using solid balls of butyl-neoprene. When more durable materials, e. g., solid balls of porcelain, hardened polished steel, and the material sold under the registered trademarks "Durestos" and "Ferodo" or wrapped stainless steel gauze were used, no wear occurred with them, but this indentation continued despite many attempts to reinforce the surface of the frames.

When balls of this type were replaced by one or three spherical spring coils having the characteristics de-

scribed above, it was found that the screens could be run for very much longer time without dismantling, e. g., 3 months, and that their general screening efficiency was very much improved over anything previously obtained. So far as could be observed there was no deterioration in the springs and practically no loss in their weight. Moreover, practically no build-up on the inclined faces of the compartments took place. Consequently substantially true surfaces were maintained for rebound of the balls. This was a distinct improvement over the use of the rubber balls which often compacted the moist powdered fertilizer and caused it to adhere to the inclined surfaces of the compartments.

A suitable form of spherical spring according to the invention is shown in elevation in Figure 1 and in plan in Figure 2 of the accompanying drawing.

The primary requirements in the hollow body are that it be abrasion resistant, resilient and of low weight.

Instead of a coil spring there may be used other resilient bodies of similar general configuration, e. g., the bodies formed from spherical, spheroidal, ellipsoidal, or even paraboloidal, shells of metal by removing a portion or portions of the shell and leaving a resilient residue, e. g., a continuous spiral strip of metal, or a spherical latticework. Alternatively, resilient bodies of similar configuration may be made by joining suitably shaped metallic elements, e. g., by welding or soldering, or by stamping. While residual elements of substantially spiral strip form are preferred, other configurations may be used provided they are sufficiently resilient to enable them to bounce under the conditions of use in the screens. There is, however, a tendency for build-up of fine material to occur on elements formed in these ways. If paraboloids are used, they should be double paraboloids.

The hollow bodies are preferably of metal, but where the temperature at which screening is conducted and the nature of the material being sieved permit they may if desired be of such materials as synthetic resins, etc.

I claim:

1. In vibrating and gyratory screens having at least one deck comprising a screening sheet, carried in a frame, and an auxiliary sheet of coarser mesh, also carried in a frame, situated beneath the first sheet and spaced therefrom, the combination of an open frame, formed with a number of compartments by longitudinal and cross members, resting on the auxiliary sheet and extending close up to the screening sheet, and situated in at least some of the compartments at least one detached metal coil spring shaped in major part so that the imaginary surface in which the outermost extremities of the coils lie is substantially a surface of revolution having double curvature which when viewed from the exterior is convex and therefore adapted for bouncing.

2. In vibrating and gyratory screens having several decks each comprising a screening sheet carried in a frame and an auxiliary sheet of coarser mesh also carried in a frame situated beneath the first sheet and spaced therefrom, the combination in conjunction with each deck of an open frame formed with a number of compartments by longitudinal and cross members, resting on the auxiliary sheet and extending close up to the screening sheet and situated in all of the compartments at least one detached metal coil spring shaped in major part so that the imaginary surface in which the outermost extremities of the coil lie is substantially a surface of revolution having double curvature which when viewed from the exterior is convex and therefore adapted for bouncing.

3. The combination as claimed in claim 2 in which the detached metal coil spring is of high carbon steel.

4. In vibrating and gyratory screens, oscillated at at least 200 cycles per minute, having at least one deck comprising a screening sheet, carried in a frame, and an auxiliary sheet of coarser mesh, also carried in a frame, situated beneath the first sheet and spaced therefrom,

the combination of: an open metal frame formed with a number of compartments by longitudinal and cross members of light gauge metal resting on the auxiliary sheet and extending close up to the screening cloth, and situated in each of the compartments at least one detached metal coil spring shaped in major part so that the imaginary surface in which the outermost diameters of the coils lie is substantially a surface of revolution having double curvature, which when viewed from the exterior is convex and therefore adapted for bouncing.

5. The combination as claimed in claim 4 in which the cross members of each open metal frame are of a section which presents interiorly to each compartment a plane face inclined at an angle of 105° to 120° to the auxiliary sheet.

6. The combination as claimed in claim 4 in which the longitudinal and cross members of each open metal frame are each of a section which presents interiorly to each compartment a plane face inclined at an angle of 105° to 120° to the auxiliary sheet.

7. The combination as claimed in claim 4 in which the detached metal coil spring is of substantially spherical shape.

8. In vibrating and gyratory screens, oscillated at at least 200 cycles per minute, having at least one deck comprising a screening sheet carried in a frame, and an auxiliary sheet of coarser mesh also carried in a frame and situated beneath the first sheet and spaced therefrom, the combination of features in each deck which comprises: stainless steel frames and sheets; an open frame formed into a number of compartments by longitudinal and cross members of light gauge stainless steel resting on the auxiliary sheet, and extending close up to the screening sheet, and situated in each of the compartments at least one detached coil spring of stainless steel shaped in major part so that the imaginary surface in which the outermost diameters of the coils lie is substantially a surface of revolution having double curvature, which when viewed from the exterior is convex and therefore adapted for bouncing.

9. In gyratory screens oscillated at at least 200 cycles per minute having at least one deck comprising a screening sheet carried in a frame, and an auxiliary sheet of coarser mesh also carried in the frame and situated beneath the first sheet and spaced therefrom, the combination in conjunction with each deck of: an open metal frame formed into a number of compartments by longitudinal and cross members of light gauge metal, each having sections which present interiorly to each compartment a plane face inclined at an angle of 105° to 120° to the auxiliary sheet, resting on the auxiliary sheet and extending close up to the screening sheet; and, situated in each of the compartments at least one detached substantially spherical metal coil spring adapted for bouncing of which the diameter of the coils of the wire forming the spring is from 0.048" to $\frac{3}{16}$ ".

10. In gyratory screens for use in the screening of hot materials having at least one deck comprising a screening sheet carried in a frame, and an auxiliary sheet of coarser mesh also carried in a frame and situated beneath the first sheet and spaced therefrom, the combination of features: screening and auxiliary sheets of metal; metal frames; in conjunction with each deck an open metal frame formed into a number of compartments by longitudinal and cross members of light gauge metal, each having sections which present interiorly to each compartment a plane face inclined at an angle of 105° to 120° to the auxiliary sheet, resting on the auxiliary sheet and extending close up to the screening sheet; and situated in each of the compartments at least one detached substantially spherical metal coil spring adapted for bouncing; the screen being oscillated at at least 200 cycles per minute.
